CONTROL DEVICE AND SYSTEM

Thomas I. Maslin, Bloomfield, and Roy N. Thomas, East Orange, N. J., assignors to General Electric Company, a corporation of New York

Application June 26, 1935, Serial No. 28,470

8 Claims. (Cl. 175—375)

Our invention relates to control systems for electric motors, more particularly to control devices and systems for selectively energizing electric motors either for continuous operation or for 5 inching or jogging operation, and has for an object the provision of a simple and reliable control device and system of this character.

It has heretofore been proposed to provide the driving motors for printing presses and similar 10 apparatus with control systems, including control devices for providing inching or jogging operation during the "make ready" period and for providing continuous operation of the driving motors thereafter. It has also been proposed in connection 15 with such apparatus to provide a push button control station for accomplishing the jogging operation. In such previous systems, one or more push buttons have been provided with means for selectively locking the push button in one position or another by some preliminary operation, such as rotating the button or adjusting a locking attachment.

It will be apparent that when such a preliminary operation is necessary to ensure jogging of 20 the driving motors, considerable reliance is placed upon the person operating the push button and consequently, there is considerable danger to other persons working around the apparatus if the operator forgets to make the preliminary adjustment before operating the push button. For 25 example, if persons working around the machine expect only the jogging operation and the operator neglects to make the preliminary adjustment, the resulting continuous operation of the 30 apparatus may endanger the safety of the persons who expected only a jogging operation.

The driving motors for such apparatus are usually controlled by an electroresponsive starting switch having interlock contacts for establishing a holding or maintaining circuit when the switch is energized, and it has been proposed to overcome the above objection to some extent by providing separate start and jog buttons, the jog button being normally inaccessible 45 to the operator and being provided with manually operable means for rendering it accessible. Both the jog and the start button are arranged to energize the starting switch directly, and the means for rendering the jog button accessible is effective when operated to interrupt the holding 50 circuit. Although such arrangements do not depend upon the skill of the operator for reliability of operation, much is yet to be desired in a push button station by means of which jogging operation may be accomplished without resort to a

preliminary operation for safety purposes and without depending upon the skill of the operator. Accordingly, it is a further object of our invention to provide a control system for accomplishing jogging operation of an electric motor, which 5 system is provided with a jog button which requires no preliminary operation by the operator, which is automatically held in jogging position each time that it is depressed and which may be released to provide continuous operation only by 10 a separate releasing operation.

In carrying out our invention in one form, we provide a control system including an electroresponsive motor-starting switch having an energizing circuit and a maintaining circuit, which 15 motor-starting switch is controlled by a push button station having a separate jog button and a separate start button. The jog button is provided with a pair of closed contacts common to both the energizing circuit and the maintaining 20 circuit and with a pair of normally open contacts for establishing an independent energizing circuit when the jog button is depressed. Means are also provided which are automatically responsive to depression of the jog button for preventing the 25 jog button from returning to its normal position to close the maintaining circuit while permitting the jog button to be moved to close and open the normally open contacts to energize and de-energize the starting switch as many times as desired. 30 Means are also provided for releasing the jog button for movement to its normal position when it is desired to operate the driving motors continuously.

For a more complete understanding of our invention, reference should now be had to the drawing in which Fig. 1 is a plan view of a push button control station provided with a jog button embodying our invention; Fig. 2 is an elevational view, partly in section, of the control station 40 shown in Fig. 1; Fig. 3 is a fragmentary sectional view showing the jog button in its latched position; and Fig. 4 is a diagrammatic illustration of a control system embodying our invention.

Referring now to the drawing, the push button station shown in Figs. 1, 2, and 3 comprises an enclosing casing 10 within which are mounted a plurality of push button switches respectively indicated by the legends "Start" and "Jog". Although any suitable type of push button switch 50 may be employed, we have shown, for purposes of illustration, a push button switch of the type described and claimed in Patent No. 1,853,964, issued April 12, 1932, to George H. Dorgeloh and Thomas I. Maslin. As shown, this push button 55

switch comprises a base 11 formed of molded insulating material having an open slot 12 at one side thereof. Secured to the base 11 on opposite sides of the slot 12 are pairs of spaced stationary contacts 13 and 14 provided respectively with suitable terminal screws 15 and 16, only one contact of each pair being shown in the drawing.

Mounted for movement between the pairs of stationary contacts 13 and 14 is a bridging contact member 17 carried by a reciprocal operating rod 18 slidably journaled in the base 11, the upper end of the rod 18 carrying the push button 19. The bridging contact 17 is of irregular shape for a purpose fully described in the above patent and is resiliently held against a collar 20 formed on the rod 18 by a compression spring 21. Surrounding the operating rod 18 is a biasing spring 22 the opposite ends of which respectively engage the insulating base 11 and the push button 19, the spring 22 being considerably stronger than the spring 21 and serving to bias the push button 19 and the movable contact 17 to the position shown in Fig. 2.

As shown, the push button 19 is provided with a flange or shoulder 23 arranged to co-operate with a latch 24 secured to an L-shaped finger 25 pivotally mounted on a pin 26 with the end of the member 25 extending through an aperture 27 in the casing 10 adjacent a guard ring 28 which surrounds the push button 19. The pin 26 is rigidly mounted on a bracket 29 which is secured to the casing 10, and a spring 30 surrounding the pin 26 normally biases the latch 24 into engagement with the circumferential surface of the flange 23 as shown in Fig. 2.

Referring now to Fig. 3, it will be apparent that when the push button 19 is depressed, the latch 24 will be moved by the spring 30 to a position to engage a side of the shoulder 23 when the push button is released, to hold the push button and the movable contact 17 in the intermediate position there shown. It will be apparent now that the push button may be depressed as many times as desired so as to engage the movable contact 17 with the stationary contacts 14, during which movement the collar 20 is carried into an opening (not shown) in the base 11, and that the movable contact 17 will be prevented from returning to its normal position; i. e., into engagement with the stationary contacts 13. When it is desired to release the push button 19, the pivoted member 25 may be moved toward the guard ring 28 so as to compress the spring 30 and withdraw the latch 24, whereupon the push button 19 is moved to its normal position by the biasing spring 22.

It is believed that a complete understanding of our invention may now be had from a description of the operation of the control system shown in Fig. 4. As shown, the control system comprises an electroresponsive starting switch 31 for controlling the energization of an electric motor 32 which is connected to a suitable source of energy 33 through the conductors 34, 35, and 36. Energization of the operating winding 37 of the starting switch 31 is controlled by the control station shown in Figs. 1, 2, and 3, which includes, in addition to the jog button 19, a start button 38 having a pair of normally open contacts 39. In addition, the energizing circuit of the operating winding 37 may be provided with a stop button 40 having normally closed contacts, and the starting switch 31 is provided as shown with a pair of interlock contacts 41.

When it is desired to operate the motor 32

continuously, the start button is depressed and an energizing circuit for the winding 37 is thereby established, which may be traced from the source of energy 33 through the conductors 36 and 42, the winding 37, the conductors 43, 44, and 45, the contacts 39 of the start button, the conductor 46, the normally closed contacts 13 of the jog button, the conductors 47 and 48, the stop button 40, and by way of the conductors 49 and 35 to the source of energy 33. Operation of the starting switch 31 to its closed circuit position closes the interlock contacts 41 and establishes a maintaining circuit for the operating winding 37 which may be traced from the source of energy through the conductors 36 and 42, the operating winding 37, the conductors 43 and 50, the interlock contacts 41, the conductor 51, the normally closed contacts 13 of the jog button, the conductors 47 and 48, the stop button 40 and by way of the conductors 49 and 35 to the source of energy 33. It will be apparent now that the motor will operate continuously until the maintaining circuit is interrupted to de-energize the winding 37.

If it is desired to inch or jog the motor before energizing the motor for continuous operation, the jogging or inching operation may be accomplished simply by depressing the jog button 19. As soon as the jog button is depressed, it will be apparent that the latch 24 will be operated by the spring 30 as described in connection with Figs. 2 and 3, to prevent the jog button from returning to its normal position when the jog button is released. Operation of the jog button to its depressed position establishes an independent energizing circuit for the operating winding 37 of the starting switch 31, which circuit may be traced from the source of energy through the conductors 36 and 42, the operating winding 37, the conductors 43, 44, and 52, the contacts 14 of the jog button, the conductors 53 and 48, the stop button 40, and by way of the conductors 49 and 35 to the source of energy. Upon energization of the winding 37, the interlock contacts 41 will again close, but it will be apparent that the previously traced maintaining circuit will be only partially completed, since the normally closed contacts 13 of the jog button are now open. The jog button may now be operated between its depressed position and the intermediate position in which it is held by the latch 24 as many times as desired to energize the winding 37 and close the switch 31 to jog the motor, and there is no danger that the maintaining circuit will be established through the interlock contacts 41 to operate the motor continuously.

As soon as the desired preliminary operation of the equipment has been obtained by jogging the motor 32, continuous operation may be obtained by moving the pivoted member 25 toward the guard ring 28 so as to release the jog button for movement to its normal position and by then depressing the start button 38. Although the energizing circuits for the winding 37 may be interrupted at any time by depressing the jog button 19 to its intermediate position, it may be desirable to provide for stopping the motor 32 at any time from some remote point. It will be apparent that this stopping of the motor may be accomplished by depressing the stop button 40 which may be located at any desired point.

While we have shown a particular embodiment of our invention, it will be understood, of course, that we do not wish to be limited thereto since

many modifications may be made and we, therefore, contemplate by the appended claims to cover any such modifications as fall within the true spirit and scope of our invention.

5. What we claim as new and desire to secure by Letters Patent of the United States is:

1. In combination, an electroresponsive motor-starting switch having an energizing circuit and a maintaining circuit, a push button operated switch having normally closed contacts common to both circuits and normally open contacts, said contacts being operable by a common push button, means automatically responsive to depression of said push button from said normal position for maintaining said normally closed contacts in open circuit position while providing for selective closure and opening of said normally open contacts by said push button, circuit connections for establishing an independent energizing circuit for said starting switch when said normally open contacts are closed, and manual means for releasing said automatic means to permit reclosure of said normally closed contacts.

2. In combination, an electroresponsive motor-starting switch having an energizing circuit and a maintaining circuit, a push button operated switch having a pair of spaced stationary contacts common to both circuits and a bridging member connected to said push button, means biasing said push button and said bridging member to cause said bridging member to engage said contacts, a second pair of spaced stationary contacts, said bridging member being depressible by said push button to disengage said first pair of contacts and to engage said second pair of contacts, means automatically responsive to depression of said push button for restricting said bridging member to movement between said second pair of contacts and an intermediate position, circuit connections for establishing an independent energizing circuit for said starting switch when said bridging member engages said second pair of contacts, said independent circuit being interrupted by release of said bridging member to said intermediate position, and manual means for releasing said bridging member for movement to said normal biased position.

3. In combination, an electroresponsive motor-starting switch having an energizing circuit and a maintaining circuit, a push button operated switch having spaced apart stationary contacts and a movable contact member cooperating with said stationary contacts connected to said push button, means biasing said push button and said contact member to provide normally closed and normally open contacts, said normally closed contacts being common to both circuits and said movable contact being depressible by said push button to open said normally closed contacts and to close said normally open contacts, means automatically responsive to depression of said push button for restricting said movable contact to movement between its depressed position and an intermediate position selectively to close and open said normally open contacts, circuit connections for establishing an independent energizing circuit for said starting switch when said normally open contacts are closed, and manual means for releasing said movable contact for movement to said normal biased position.

4. A control system for an electroresponsive motor-starting switch comprising a "start" button and a "jog" button, means operable by said "jog" button comprising spaced apart stationary contacts and a movable contact member con-

nected to said "jog" button, means biasing said "jog" button and said contact member outwardly to cause said contact member to provide normally closed and normally open contacts, said movable contact being depressible by said "jog" button to open said normally closed contacts and to close said normally open contacts, circuit connections including said normally closed contacts for establishing an energizing circuit for said switch when said "start" button is depressed, circuit connections also including said normally closed contacts for establishing a holding circuit when said switch is energized, whereby said switch is maintained energized after said "start" button is released, circuit connections for establishing an independent energizing circuit for said switch when said movable contact is operated by said "jog" button to close said normally open contacts, means automatically responsive to depression of said "jog" button for restricting said movable contact to movement between said depressed position and an intermediate position whereby said holding circuit is rendered ineffective, said movable contact being depressible from and releasable to said intermediate position selectively to establish and interrupt said independent energizing circuit, and manual means for releasing said movable contact for movement to said normal position.

5. A control system for an electroresponsive device comprising push button means for partially completing an energizing circuit for said device, means operable with said device for partially completing a holding circuit therefor, a second push button means, means normally biasing said second push button means outwardly to one position to complete said energizing and said holding circuits when said first push button means is operated to energize said device and operate said holding circuit means, said second push button being depressible to open both of said circuits, latching means automatically responsive to movement of said second push button to depressed position for restricting said second button to movement between said depressed position and an intermediate position, whereby said second push button is prevented from completing said circuits, circuit connections for completing an independent energizing circuit for said device when said second push button is in said depressed position, said independent energizing circuit being interrupted by release of said second push button to said intermediate position, and means for releasing said latching means whereby said second push button returns to said biased position to prepare said first-mentioned circuits for closure upon operation of said first push button.

6. A push button switch comprising a pair of spaced apart stationary contacts, a movable contact, means biasing said movable contact to one position to engage one of said stationary contacts, a push button for operating said movable contact to another position to engage another of said stationary contacts, means automatically responsive to an operation of said push button to operate said movable contact from said one position for restricting said contact to movement between said other position and an intermediate position to prevent reengagement of said movable contact with said one stationary contact, and manual means independent of said push button for operating said restricting means to permit said movable contact to return to said one position.

7. A push button switch comprising a casing

75

having an aperture, a push button movable through said aperture, a plurality of spaced apart stationary contacts, a movable contact within said casing, means biasing said movable contact to one position to engage one of said stationary contacts, a connection between said push button and said movable contact whereby said movable contact is operable by said push button to another position, means including a spring pressed latch within said casing responsive to an operation of said movable contact from said one position for limiting said movable contact to movement between said other position and an intermediate position to prevent reengagement of said movable contact with said one stationary contact, and means operable from outside of said casing for withdrawing said latch to permit said movable contact to return to said one position.

8. A push button switch comprising a casing having an aperture, a push button movable through said aperture and having a shoulder

formed thereon within said casing, a contact within said casing, means biasing said contact to one position, means connecting said contact to said push button whereby said contact is operable by said push button to another position, a spring pressed latch normally engaging the circumference of said shoulder on the push button, said latch being automatically operable when said push button is depressed to a position to engage a side of said shoulder when said push button is released, whereby said contact is thereafter limited to movement between said other position and an intermediate position, and means movably extending through said casing adjacent said push button and operable from outside said casing for withdrawing said latch from engagement with said shoulder to permit said contact to return to said one position.
